UNITED STATES PATENT OFFICE

2,436,782

LOCK STITCH SEWING MACHINE

Guido J. Barbati, Beverly, Mass., assignor to
 United Shoe Machinery Corporation, Flemington, N. J., a corporation of New Jersey

Application November 23, 1946, Serial No. 712,005

3 Claims. (Cl. 112—36)

1

The present invention relates to improvements in lock-stitch sewing machines and is herein disclosed as embodied in a hook needle shoe sole sewing machine of the rotary horn type in which each loop of needle thread is pulled from the shuttle partially back toward the upper surface of the work by a take up, enough slack thread being left remaining in the loop outside the work to provide thread for one side of the needle loop in the next succeeding stitch. The threaded needle, as it is moving within the substance of the work, therefore does not cause the thread to slide and become frayed within its hook.

The object of the invention is to provide simple means for enabling easy adjustment of such machine for optional use with relatively thin or thick work. When relatively thin work is being sewn, a shorter needle is employed than with thicker work. The use of a shorter needle is desirable to enable the needle to be more resistant to bending stresses, particularly where a needle of smaller wire gage is employed. For thicker work, a needle of larger gage is employed and, consequently, it is possible to use one having a greater length without losing stiffness. In either case, however, the needle is reciprocated through a fixed stroke, the needle hook moving the same distance toward and away from the work supporting horn of the machine. When thicker work is being sewn, however, the length of the needle loop left remaining outside the work after the take up acts is less than with thin work and, in some instances, may not be sufficient to enable the threaded hook of the needle to move through the substance of the work without causing the thread to slide in the needle hook.

Accordingly, in carrying out the object of the present invention, a readily removable shim is provided between a bracket for supporting the shuttle and the upper portion of the column on which the entire machine is mounted, so arranged that as each needle loop is passed over the shuttle while the shim is in place sufficient thread will be pulled from the supply to enable the threaded needle hook to be moved through thin work without causing the thread to slide in the needle hook. With the shim removed, for sewing thicker work, the shuttle will likewise pull off from the supply sufficient thread to enable the needle to move through the substance of the work without causing the thread to slide in the needle hook.

This and other novel combinations, and arrangements of parts, as hereinafter claimed, will readily be understood from the following de-

scription taken in connection with the accompanying drawings, in which:

Fig. 1 is a view in right side elevation of so much of the upper portion of an improved shoe sewing machine as is necessary to illustrate the embodiment of the present invention;

Fig. 2 is a front detail view illustrating the manner in which the machine operates; and

Fig. 3 is a similar view of the shuttle and work supporting horn with the needle and needle supporting bar omitted.

The machine illustrated in the drawing is a lockstitch shoe sewing machine of a type similar to that disclosed in United States Letters Patent No. 1,885,927, granted November 1, 1932, upon application of Bernard T. Leveque, and No. 1,914,936, granted June 20, 1933, upon application of Fred Ashworth. In this machine a shoe or other similar work is supported upon a rotary horn 4 mounted on the column and arranged to extend within the shoe which is held in engagement with the horn by a presser foot 6 acting to grip the work while the stitch forming devices act. The stitch forming and work supporting devices are mounted for operation upon a frame comprising a main column 7, the construction of which is more fully disclosed in the patents referred to.

The stitch forming devices comprise a straight needle 8, a loop taker in the form of a shuttle 10, acting to carry each loop of needle thread about a locking thread, a loop spreader 12, and a take-up 14 acting to pull each loop of needle thread together with the encircled locking thread from the shuttle partially back through the work with a portion 15 of the needle loop left remaining outside the work. After the take-up has acted, the shoe is fed in preparation for a new stitch formation and the needle again penetrates the work, entering the horn to receive a new loop of thread. During the succeeding reTRACTING movement of the needle while its threaded hook is moving through the work, thread is drawn from the portion 15 of the preceding loop which remains outside the work so that no sliding movement of the thread takes place within the needle hook. In this way fraying and excessive wear on the thread are avoided. Thus, the loop from the preceding stitch is drawn nearly to the surface of the work by the needle. Thereafter, the loop spreader engages the loop of thread carried by the needle and spreads it for reception of the shuttle. The shuttle continues the withdrawal of the preceding loop of needle thread together with the encircled locking

thread and pulls the interlocked threads into the work, finally setting the preceding stitch (Fig. 3). After setting each preceding stitch, continued movement of the shuttle pulls a length of thread from a supply (not shown) past a thread lock 16, sufficient in amount to form the next stitch.

The machine of the patents referred to is extremely satisfactory in operation on shoe soles and other heavy material under $\frac{5}{8}$ of an inch in thickness and with proper adjustments may be made to operate successfully on thicker work. With the length of needle ordinarily employed in this machine, however, the upper surface of work thicker than $\frac{5}{8}$ of an inch frequently is engaged by the enlarged shank portion of the needle, indicated at 18 in Fig. 2, when the needle is in its lowermost work penetrating position. With work approaching $\frac{5}{8}$ of an inch in thickness this enlarged shank portion of the needle actually enters the work thereby forming undesirable enlargements in the needle perforations. To avoid this difficulty it is necessary to employ a longer needle so that the enlarged shank 18 of the needle will not engage the work.

As in the patented machine the needle 8 is secured to the lower end of reciprocating needle carrying bar 19 to which is clamped an actuating block 20. To accommodate a longer needle the needle bar must be raised with relation to its reciprocating mechanism. This is accomplished conveniently in the illustrated machine by loosening the clamp block 20 on the needle bar and moving the bar within the block before reclamping until the hooked lower end of the needle will occupy the same positions at the upper and lower ends of its stroke as did the shorter needle previously employed. Thus, during its reTRACTING stroke, the hook of the needle in the machine must rise and fall to the same positions regardless of the length of needle employed or the thickness of the work operated upon. The stroke of the needle, however, is ample to take care of the thickness of any work upon which the machine is capable of operating successfully.

With work having a thickness greater than $\frac{5}{8}$ of an inch, the portion 15 of needle loop remaining outside the work in each preceding stitch is insufficient to provide slack thread for the needle during its reTRACTING stroke in the formation of a succeeding stitch. For this reason, with work thicker than $\frac{5}{8}$ of an inch even with a longer needle, difficulty still is encountered by reason of a sliding movement of the thread in the needle hook while the threaded needle hook is passing through the substance of the work.

To provide simple and effective means for adjusting the machine for use with work thicker than $\frac{5}{8}$ of an inch, according to a feature of the present invention, the shuttle is arranged to pull through a greater length of the needle loop when the machine is adjusted for thick work than for thin work. For this purpose the shuttle is raised bodily when the machine is being adjusted for thicker work to a position higher than when thin work is being operated upon. Thus, each loop of thread is carried over the shuttle to a higher position and it is not drawn down as far as before during the thread-pulling stroke of the take-up, but is left with a longer portion 15 remaining outside the work. Accordingly, when the threaded needle is being reTRACTED from the work in the succeeding stitch, there is ample slack thread left between the needle and the previously formed

stitch to prevent sliding movement of the thread in the needle hook.

To enable raising the shuttle bodily when thick work adjustments are being made, the shuttle is mounted to rotate in a bracket 22 clamped to the underside of the upper portion of the column for the machine but spaced therefrom by a readily removable shim 24 equal to the additional length of the longer needle ordinarily employed while operating upon work thicker than $\frac{5}{8}$ of an inch. In the embodiment illustrated, this shim is approximately $\frac{1}{4}$ of an inch thick, to enable the use of a needle $\frac{1}{4}$ of an inch longer which is effective for operation upon $\frac{5}{8}$ of an inch work to prevent engagement by the shank of the needle. Work of $\frac{5}{8}$ of an inch thickness is illustrated in the dot-dash line of Fig. 2 and with work of such thickness it is readily apparent that the portion 15 of needle loop left remaining outside the work when the machine is adjusted for $\frac{5}{8}$ of an inch work is insufficient to provide slack thread for the needle during its reTRACTING stroke.

The bracket 22 which supports the shuttle also provides a mounting for the loop spreader 12. Accordingly, when the shim 24 is removed, the loop spreader 12 is raised along with the shuttle to the dot-dash positions of Fig. 1 so that it retains its proper relative relationship to the shuttle, thus acting effectively with the needle to open the loop for the reception of the shuttle. The loop spreader and shuttle being raised bodily when the shim 24 is removed cause the length of thread drawn thereby through the work to be increased by an amount double the increased length of the needle.

The nature and scope of the invention having been indicated and a machine embodying it having been specifically described, what is claimed is:

1. A lockstitch sewing machine having a main column, the upper portion of which contains stitch forming devices including a hook needle acting while its threaded hook is being reTRACTED from the work to draw thread from the loop of needle thread in the preceding stitch, a shuttle acting to pull off thread from the supply for the next stitch, a take-up for pulling each needle loop from the shuttle partially back through the work, a shuttle supporting bracket on the upper portion of the column and a shoe supporting horn mounted on the column to extend within the shoe, in combination with means for enabling easy adjustment of the machine to optional use for thicker work, comprising a readily removable shim between the shuttle supporting bracket and the upper portion of the column, to cause the shuttle to draw each loop of needle thread to a higher position relatively to the horn for the thicker work.

2. A lockstitch sewing machine having a main column, the upper portion of which contains stitch forming devices including a hook needle acting while its threaded hook is being reTRACTED from the work to draw thread from the loop of needle thread in the preceding stitch, a shuttle acting to pull off thread from the supply for the next stitch, a take-up for pulling each needle loop from the shuttle partially back through the work, a shuttle supporting bracket on the upper portion of the column and a shoe supporting horn mounted on the column to extend within the shoe, in combination with means for enabling easy adjustment of the machine to optional use with a longer needle for thicker work, comprising a readily removable shim between the shuttle supporting bracket and the upper portion of the

column, the thickness of said shim being equal to the additional length of the longer needle employed, to cause the length of thread pulled through the work by the shuttle to be increased by an amount double the increased length of the longer needle.

3. A lockstitch sewing machine having a main column, the upper portion of which contains stitch forming devices, including a straight hook needle acting while its threaded hook is being retracted from work to draw thread from the loop of needle thread in the preceding stitch, a shuttle acting to set the preceding stitch and thereafter to pull off thread from the supply for the next stitch, a take-up for pulling each needle loop from the shuttle partially back through the work, a loop spreader for engaging each needle loop to

spread it for entry of the shuttle, a shuttle and loop spreader supporting bracket secured to the under side of the upper portion of the column, and a shoe supporting horn arranged on the column to extend within the shoe, in combination with means for enabling easy adjustment of the machine to optional use for thicker work, comprising a readily removable shim between the shuttle supporting bracket and the upper portion 10 of the column, for increasing the space between the horn on the one hand and the loop spreader and shuttle on the other hand, to cause the shuttle to draw each loop of needle thread to a higher position relative to the horn when the 15 shim is removed for the thicker work.
